Patented Oct. 1, 1912.

UNITED STATES PATENT OFFICE.

ADMIRAL N. DE GROFF AND CORNELIA A. CRANDALL, OF PINE RIVER, WISCONSIN.

DRAFT ATTACHMENT.

1,040,163.

Specification of Letters Patent.

Patented Oct. 1, 1912.

Application filed March 20, 1912. Serial No. 685,120.

To all whom it may concern:

Be it known that we, ADMIRAL N. DE GROFF and CORNELIA A. CRANDALL, citizens of the United States, residing at Pine River, 5 in the county of Waushara and State of Wisconsin, have invented certain new and useful Improvements in Draft Attachments, of which the following is a specification, reference being had to the accompanying drawings.

This invention relates to new and useful improvements in three horse eveners and an attachment therefor, whereby if either of the forward wheels of a vehicle strike an 15 obstruction the draft of all the horses is thrown on the obstructed wheel or that side of the vehicle till it draws as easy as the side not obstructed.

Another object of the invention is to provide a draft attachment of this character which will possess advantages in points of efficiency and durability, is inexpensive of manufacture and at the same time is simple in construction and operation.

With the above and other objects in view the invention consists of the novel features of construction and the combination and arrangement of parts hereinafter more fully described, pointed out in the claim and 30 shown in the accompanying drawing in which:—

Figure 1 is a top plan view of the front portion of a vehicle frame showing our improved draft attachment applied thereto;

35 Fig. 2 is a longitudinal sectional view; and Fig. 3 is a detail perspective view of the draft member.

Referring more particularly to the drawing 1 indicates the forward axle and 2 the forward ends of the hounds, between which is pivotally secured the inner end of the tongue 3. A draft member 4 is provided which comprises an elongated body portion 5, having the two curved diverging arms 6 formed integral therewith and projecting from each side thereof, said arms having their outer ends extending downwardly so as to project below the lower side of the tongue.

50 An extension 7 projects rearwardly from the body portion, at the intersection of the arms 6, said extension being disposed intermediate of the two arms 6 and provided with a longitudinal slot 8 adapted to receive the headed bolt 9 carried by the tongue. By this construction it will be seen

that the draft member 4 is mounted on the tongue for longitudinal movement. An elongated plate 10 is provided having one end secured to the tongue adjacent the inner end thereof, and having its other end mounted on the bolt 9 and disposed between the head of the bolt and the extension 7.

Connected to the outer ends of the arms 6 by means of the hooks 11 are the draft 65 chains 12, said chains having their other ends connected to the collars 13 by means of the hook 14 engaged in openings formed in the ends of the collars. The collars 13 are mounted on the axle adjacent the inner end 70 of the spindle so that the pull will be as near the wheels as possible.

Secured to the forward end of the draft member 4 by means of the king bolt 15 is the main evener bar 16 which is provided 75 at each end with a plurality of openings 17. Pivotally secured to one end of the bar 16 by means of the clevis 18 is the short evener lever 19, having a swingle tree 20 pivotally secured to its outer end. It will 80 be adjusted longitudinally on the bar 16 by placing the pin 21 in any one of the openings 17. Pivotally secured to the other end of the bar 16 by means of the clevis 22 is the long evener lever 23, which is provided 85 at its central portion with a plurality of openings 24 adapted to register with the openings 17 in the bar 16, whereby the lever 23 can be adjusted longitudinally on the bar 16 by having the pin 25 passing through 90 any one of the openings 17 and 24. Pivotally secured to the outer end of the evener lever 23 is the double-tree 26.

A connecting bar 27 is connected to the inner ends of the levers 19 and 23 by means 95 of the short links 28, which extend at right angles to the connecting bar 27 and the levers 19 and 23, said bar being pivotally mounted upon the king bolt 15. It is often the case where three horses are hitched to 100 an evener of this character that one or more of the horses will be heavier than the others, if for instance two heavy horses are secured to the double-tree 26 and a lighter horse secured to the swingle-tree 20 the lever 23 105 would be moved in toward the center of the bar 16 and the lever 19 would be moved out toward the end of the bar 16. Thus, it will be seen that the pull of all the animals will be equally distributed, and by moving 110 the pins 21 or 25 any horse can be given the advantage.

It is to be fully understood that the three horse evener herein shown and described is the main feature of our invention while the draft attachment shown and described is 5 designed especially for use with our improved evener, and it will also be understood that this draft attachment can be used with any number of horses described.

From the above description taken in connection with the drawings it will be seen that by having the evener secured to the outer end of the draft member the pull will be directly from the outer ends of the axle, thus if either of the forward wheels 15 strike an obstruction the draft of all the horses is thrown on that wheel or that side until it draws as easily as the side not obstructed. The vehicle is thus directly actuated through the medium of the forward 20 axle 1, and because of the equalized operative strain or draft upon the axle 1 the pole 3 is prevented from lateral oscillation or wabbling and the consequent interference of the same with the draft animals.

25 It will be understood that this draft attachment can be used on heavy farm machinery, such as binders, mowers, manure spreaders, etc., or it may be used on wagons or other lighter vehicles.

30 While we have shown and described the preferred form of our invention it will be obvious that various changes in the details of construction and in the proportions may be resorted to for successfully carrying our

invention into practice without sacrificing 35 any of the novel features or departing from the scope thereof.

Having thus described our invention, what we claim is:—

A device of the character described, including an evener bar having a plurality of openings formed therein at each end, levers disposed on the ends of said evener bar and each lever formed with a plurality of openings extending therethrough, clevises extending through registering openings of the levers and evener bar and designed to be shifted in and out, whereby to change the fulcrumed points of said levers intermediate of the ends of the latter, a swingletree 50 connected to the outer end of one of said levers, a doubletree connected to the outer end of the other lever, a connecting bar mounted between the inner ends of said levers and pivotally connected intermediate 55 of its ends to the evener bar, and short links extending at right angles to the levers and connecting bar and pivotally connecting the ends of the connecting bar to the levers, as and for the purpose set forth. 60

In testimony whereof we hereunto affix our signatures in the presence of two witnesses.

ADMIRAL N. DE GROFF.
CORNELIA A. CRANDALL.
